UNITED STATES PATENT OFFICE.

FRED A. DENNETT, OF SHEBOYGAN, WISCONSIN.

DESIGN FOR A VENEER-PRESSING MEMBER.

SPECIFICATION forming part of Design No. 34,944, dated August 13, 1901.

Application filed March 28, 1901. Serial No. 53,371. Term of patent 14 years.

To all whom it may concern:

Be it known that I, FRED A. DENNETT, a citizen of the United States of America, residing at Sheboygan, in the county of Sheboygan and 5 State of Wisconsin, have invented and produced a certain new, useful, and original Design for an Article of Manufacture—to wit, a Veneer-Pressing Member—of which the following is a specification, reference being had 10 to the accompanying drawings, forming a part hereof.

In said drawings, Figure 1 is a plan view of 15 a veneer-pressing member embodying my design. Fig. 2 is a longitudinal sectional view taken on line 2 2 in Fig. 1. Figs. 3 and 4 are cross-sectional views taken on lines 3 3 and 4 4 in Fig. 2, these four views being deemed necessary for full illustration.

The leading and essential feature of my 20 design for a veneer-pressing member consists of the peculiar and novel formation of the lower surface of the same.

The portion of the lower surface of my 25 design bounded by an imaginary straight line joining the points *d d* and the lines *d g, g h*, and *h d* is rectangular, and its surface, aside from a raised portion hereinafter referred to, is in one plane. The raised portion starting from an indefinite substantially straight 30 line joining points *a a* is edge-outlined as follows: The sides start from the points *a a*

and proceed backward on substantially straight lines substantially parallel with the sides *d g* and *d h* to points *b b* and from the points *b b* around on a semicircular line 35 touching a point *c*. The slopes of the raised portion are gradual and shaped substantially as shown in Figs. 2, 3, and 4.

The front portion or edge of my design, starting from the imaginary straight line 40 joining points *d d*, proceeds forward and down on irregularly-curved surfaces straight across from side to side to a straight edge joining points *e e*. The front portion, bounded by lines *f i, f e, i e*, and *e e*, is rectangular and its 45 plane is parallel with the lower flat surface.

The several minor features of my design may be stated, as follows: The top is flat and its plane is parallel with the planes of the flat portion of the lower surface. The sides 50 are parallel planes and stand at right angles to the top, as do the ends.

Having thus described my design, what I claim is—

The design for a veneer-pressing member, 55 substantially as shown and described.

Signed by me at Port Washington, Wisconsin, this 28th day of February, A. D. 1901.

FRED A. DENNETT.
